Lahaska, Pa. 18931

Filed Feb. 24, 1969, Ser. No. 15,883

Term of patent 14 years

Int. Cl. D30—03

U.S. Cl. D30—21

FIG. 1

FIG. 5

FIG. 1 is a perspective view of a hackamore attachment to a bit, showing my new design.

FIG. 2 is a side elevational view thereof; the other side appears exactly the same.

FIG. 3 is a top plan view thereof.

FIG. 4 is a bottom plan view thereof.

FIG. 5 is an end elevational view thereof. The other end appears exactly the same.

The broken lines in the several views are disclosed for illustrative purposes only and form no part of the claimed design.

I claim:

The ornamental design for a hackamore attachment to a bit, as shown and described.
